COMMUNICATION SYSTEM FOR RAILWAY
YARDS

Ralph R. Kemmerer, Swissvale, Pa., assignor to
The Union Switch & Signal Company, Swiss-
vale, Pa., a corporation of Pennsylvania

Application March 4, 1937, Serial No. 129,021

13 Claims. (Cl. 246—8)

My invention relates to communication systems for railway yards.

A feature of my invention is the provision of apparatus for communication from any one of a plurality of control stations located about a railway yard to a vehicle such as, for example, a shifting locomotive on any yard track. A further feature of my invention is the provision of apparatus for communication systems of the type here contemplated which operates on the closed circuit principle. A still further feature of my invention is the provision of apparatus for systems of the type here involved to indicate at each control station that the system is in working order, and to also indicate at each station when the apparatus at that station is conditioned for sending and when communication is in progress from one of the other control stations. Other features and advantages of my invention will appear as the specification progresses.

I will describe one form of apparatus embodying my invention, and will then point out the novel features thereof in claims.

Referring to the drawing, Fig. 1 is a diagrammatic view of one form of apparatus embodying my invention when applied to a receiving yard leading to a hump track, and along which track two control stations are located. Fig. 2 is a diagrammatic view of the apparatus and circuits provided at the control stations of Fig. 1 for governing the transmitting apparatus thereof. In each of the two views, similar reference characters designate similar parts.

My invention is especially useful for directing the movements of shifting locomotives in classification yards where a hump is used. It will be understood that the invention is not limited to this one application and many places for its use will suggest themselves. This one embodiment of the invention will serve, however, to illustrate the many places where the invention is useful.

Referring to Fig. 1, the reference character RY designates a receiving yard which, as here shown, comprises three parallel tracks 1T, 2T and 3T. Traffic normally enters the yard RY from a main track (not shown) to the right, as viewed in Fig. 1. Traffic leaves the yard RY over a hump track HT, and from thence it moves into a classification yard (not shown) to the left of Fig. 1. In accordance with the usual practice, cars are collected on the several tracks of the receiving yard RY and are then pushed over the hump by a shifting locomotive, the movement of the cars from the hump to the classification yard being governed by car retarders or car riders, as desired.

The usual track scale may also be provided in the hump track HT. Although only three tracks are shown in the yard RY, it will be understood that the yard may be provided with additional tracks, each of which is connected with the hump track 5 by the customary ladder track.

The purpose of the present invention is to enable operators stationed at the control points along the hump track to communicate with the crew in the cab of a shifting locomotive on any 10 one of the tracks of the receiving yard for directing the movement of the locomotive in pushing cars over the hump.

The rails of the tracks of the receiving yard are included in a normally closed transmitting 15 circuit. This transmitting circuit may be traced from the upper right-hand output terminal of transmitting apparatus TA over a line wire 4 to a point A at the end of the receiving yard remote from the hump, and at which point the line wire 20 4 is connected to at least one of the track rails of each of the tracks 1T, 2T and 3T by the usual rail connections. From the point A the circuit extends through the receiving yard over the track rails of the several tracks in multiple to a point D 25 along the hump track where a wire 5 is connected to each rail of the hump track in the usual manner, and the circuit is then completed over wire 5 which is connected with the lower right-hand output terminal of the transmitting apparatus TA. 30 The track rails may be bonded by the usual rail bonds to improve their electrical conductivity, but they need not be insulated into track sections by the customary insulating rail joints. This transmitting circuit is intended for cooperation 35 with vehicle carried apparatus responsive to alternating current flowing in the rails, energy being preferably transferred from the track rails to the vehicle carried apparatus inductively through the medium of an inductor mounted on 40 the vehicle in inductive relation with the track rails. It will be observed that the transmitting circuit is not shunted by the wheels and axles of 45 a vehicle, and the rails of each track form a branch path in the transmitting circuit so that energy will be transferred to a vehicle provided with such receiving apparatus irrespective of the track occupied by the vehicle, whether the inductor is at one end or the other of the vehicle, whether the vehicle is proceeded or followed by 50 other vehicles on the same track, and whether the other tracks are occupied by other cars.

The structure of the vehicle carried receiving apparatus is immaterial and may be receiving apparatus of the type disclosed in the United States 55

application for Letters Patent Serial No. 133,214, filed March 26, 1937 by Willard F. Place for Receiving apparatus for communication systems. Such vehicle carried receiving apparatus is normally conditioned for reception and is responsive to a carrier signaling current of a predetermined frequency for governing a cab indicator, and is conditioned for reception of a carrier telephone current when the signaling current is discontinued, the voice frequencies of such carrier telephone current being reproduced at a loud speaker or telephone receiver. The cab indicator, when displayed, indicates that the transmitting circuit is energized with signaling current and the circuit is in working order for transmission of the telephone current. The cab indicator, when extinguished, indicates that the signaling current is discontinued, due either to a failure of the system or that an operator at a wayside station is about to initiate telephone communication. It is clear that such vehicle carried receiving apparatus may be used for signaling as well as for telephone communication, the cab indicator, when illuminated, being a signal for the shifting locomotive to proceed in pushing cars over the hump and, when extinguished, being a signal for the locomotive to stop unless the extinguishing of the indicator is immediately followed by verbal instructions. In the present invention, one-way communication only is contemplated and the vehicle is not provided with transmitting apparatus.

The transmitting apparatus TA would be located at any convenient point and preferably would be mounted in suitable housing in the vicinity of the point D. The transmitting apparatus TA may be any one of several well-known types and will be referred to more fully herein-after.

40 Two control stations S1 and S2 are located along the hump track HT at desired points such as, for example, the yard office and the track scales. As here shown, these control stations are spaced apart and are remote from the transmitting apparatus TA. For the purpose of enabling operators stationed at the control stations S1 and S2 to communicate with the crew of a shifting locomotive in the yard RY through the medium of the transmitting circuit, these stations are each provided with control apparatus to be described later, which is connected with the transmitting apparatus TA over line circuits indicated as a whole by the reference character L in Fig. 1. Although only two control stations are provided, it will be understood the invention is not limited to two control stations, and other stations may be established at other points, as desired.

60 Referring to Fig. 2, the transmitting apparatus TA comprises a modulator-oscillator MO, an amplifier AM, an output transformer T1 and an input transformer T2. The modulator-oscillator MO and the amplifier AM may each be any one of several well-known types for such devices, and are shown conventionally only for the sake of simplicity, since the specific structure of each such device forms no part of my present invention. The modulator-oscillator MO and the amplifier AM may be of the type disclosed in the 70 United States Letters Patent No. 2,064,639, granted December 15, 1936, to Whitelock et al. for Communication systems. It is believed to be sufficient for the instant application to point out that the modulator-oscillator MO includes an oscillator or generator of carrier frequency cur-

rent and means for modulating such carrier current by voice frequencies. The modulator-oscillator MO is also provided with circuit means wherewith the original carrier frequency may be shifted a few cycles up or down to produce a signaling current, such signaling current being the equivalent of the original carrier modulated by a predetermined voice frequency. This circuit means is such that when a control relay R1 is energized to close its front contact 10 the capacitance or inductance of the associated oscillating circuit is varied and the carrier frequency is shifted, but when the relay R1 is deenergized and released to open the front contact 10 carrier current of the original frequency is generated. A 15 voice frequency current supplied to the primary winding 11 of the input transformer T2, in a manner later to appear, induces electromotive forces of like frequencies in the secondary winding 12 of the transformer T2, and these electromotive forces are applied to the input side of the modulator-oscillator for modulating the carrier current. The output side of the modulator-oscillator is connected over wires 6 and 7 to the input side of the amplifier AM, which may be two 20 electron tubes connected in the usual push-pull arrangement. The output side of the amplifier AM is connected with the primary winding 8 of the output transformer T1, the secondary winding 9 of which is connected to the wires 4 and 5 30 of the transmitting circuit traced hereinbefore. It follows that normally, that is, when relay R1 is energized and its front contact 10 is closed, the transmitting apparatus TA is operative to supply the transmitting circuit with a signaling 35 current of a predetermined frequency, but that when relay R1 is released and its front contact 10 is opened the transmitting apparatus is conditioned for supplying the transmitting circuit with a carrier telephone current resulting from 40 modulation of the carrier by voice frequencies supplied to the input transformer T2.

The control stations S1 and S2 are each provided with control apparatus which includes, in each case, a push button type circuit controller 45 and two indication lamps as well as a microphone. The push buttons PB1 and PB2 at the stations S1 and S2, respectively, are of the spring return type and carry normally closed contacts as well as contacts closed when the push button is 50 depressed. The indication lamps L1 and L2 at the stations S1 and S2, respectively, when illuminated, indicate that the relay R1 is energized to condition the transmitting apparatus for supplying the transmitting circuit with the signaling 55 current, and hence indicate to the operators at these stations that the system is in working order. The lamp LA1 at station S1, when illuminated, indicates that the circuit for the associated microphone M1 is effective. Likewise, the lamp LA2 at station S2, when illuminated, indicates that the circuit of the associated microphone M2 is effective. The indication lamps at each control station also indicate when communication is 60 in progress at the other control station.

65 When the push buttons PB1 and PB2 are normal, that is, in the position illustrated in Fig. 2, a circuit is completed from the B terminal of any convenient source, such as a battery not shown, over normally closed contact 13 of push button PB1, wire 14, normally closed contact 15 of push button PB2, line wire 16, winding of relay R1 and to the C terminal of the same source of current, and the relay R1 is energized. With relay R1 70 picked up to close front contact 10, the trans- 75

mitting apparatus TA is conditioned for supplying signaling current in the manner described hereinbefore. The closing of front contact 17 of relay R1 completes a circuit for the lamps L1 and L2, and which circuit may be traced from the B terminal of the current source over normally closed contact 13 of push button PB1, wire 14, normally closed contact 15 of push button PB2, wire 16 to wire 25, and thence through lamp L2 at 5 station S2 to line wire 18, or through lamp L1 at station S1 to wire 18, front contact 17 of relay R1 and to the C terminal, and the two lamps L1 and L2 are illuminated in parallel. Consequently, under the normal condition of the system the 10 transmitting circuit is continuously supplied with signaling current to influence the cab indicator of any shifting locomotive in the yard RY, and the lamps L1 and L2 at the respective control stations are continuously illuminated to indicate that 15 the system is in working order.

An operator at the station S1 wishing to signal to the crew of a shifting locomotive in yard RY would depress the push button PB1 to open contact 13 and deenergize the control relay R1, the 20 release of relay R1 being followed by the termination of the signaling current and the extinguishing of the cab indicator on such locomotive. As stated hereinbefore, extinguishing the cab indicator may be a signal to the crew of the shifting locomotive to stop. Release of the push button 25 PB1 by the operator at station S1 would re-establish the display of the cab indicator. It is clear that, by operating push button PB1 for long and short intervals according to a prearranged code to establish corresponding displays of 30 the cab indicator, code signaling may be effected for governing the movement of the shifting locomotive.

When the push button PB1 is depressed and 35 contact 13 is opened, the lamps L1 and L2 are both extinguished. The extinguishing of the lamp L2 at station S2 would indicate to the operator at station S2 that the operator at station S1 is signaling or that there is a failure of the system.

If the operator at station S1 wishes to talk to the crew on the locomotive, he would depress the push button PB1 and then talk into the microphone M1. Depressing the push button PB1 40 closes a normally open contact 19 and completes a microphone circuit extending from the B battery terminal over normally closed contact 21 of push button PB2 at station S2, wire 22, contact 19 now closed, microphone M1, line wire 20, primary winding 11 of input transformer T2 and to the C terminal. The microphone circuit thus completed is effective to modulate the carrier current generated in the modulator-oscillator MO 45 with the voice frequencies produced by speaking into the microphone M1, with the result that the transmitting circuit is now supplied with a carrier telephone current which is picked up at the locomotive and the voice frequencies reproduced in the vehicle carried receiving apparatus in the manner described hereinbefore. The lamp LA1 is supplied with current in parallel with microphone M1 when the contact 19 is closed and is illuminated 50 to indicate to the operator at station S1 the effective condition of the microphone circuit. It is to be observed that the circuit for microphone M1 55 and lamp LA1 can be completed only when the push button PB2 at the station S2 is in the normal position and contact 21 thereof is closed. Thus, should the lamp LA1 not light up when the push button PB1 is depressed, the operator at station 60

S1 would know that his microphone is ineffective, due either to communication being in progress from the other control station or that there is a failure of the system. When the operator at station S1 has completed signaling or telephoning to the crew of the locomotive, he would release the push button PB1 and the normal condition of the system would at once be reestablished.

The operator at station S2 may signal to the 10 crew of the locomotive by operation of the push button PB2 to control the relay R1, since the normally closed contact 15 of push button PB2 is interposed in the control circuit for relay R1. The lamps L1 and L2 are also responsive to operation 15 of the push button PB2 in the same manner they respond to operation of the push button PB1. The operator at station S2, to initiate telephone communication, would depress the push button PB2 and then speak into the microphone M2. 20 The push button PB2, when depressed, closes a normally open contact 23 and completes a circuit for the microphone M2, and which circuit extends from B battery terminal over normally closed contact 24 of push button PB1, wire 22, contact 23 now 25 closed, microphone M2, line wire 20, primary winding 11 of transformer T2 and to the C terminal. Thus, operation of the push button PB2 not only deenergizes relay R1 to discontinue the 30 sending of the signaling current but renders the microphone M2 effective to modulate the carrier current, with the result that the transmitting circuit is supplied with a carrier telephone current having the voice frequencies produced by the operator at station S2 speaking into the microphone M2. The lamp LA2 is illuminated when 35 contact 23 is closed and indicates to the operator at station S2 the effective condition of the microphone M2. Again, it is to be observed that the circuit for the microphone M2 and lamp LA2 at 40 station S2 can be completed only if push button PB1 is in the normal position and the contact 24 thereof is closed. Hence, if the lamp LA2 fails to light up in response to operation of the push button PB2, the operator at station S2 would know 45 that communication is in progress from the station S1 or that the system is inoperative. With such connection between the two control stations S1 and S2, the undesirable confusion which might result, should transmission of instructions 50 to the shifting locomotive be attempted from both stations simultaneously, is avoided. Furthermore, it is to be observed that when an operator at either station is transmitting speech the operator at the other station may depress his push button 55 and terminate the conversation from the other station and set up a stop signal on the locomotive.

Apparatus constructed in the manner disclosed in Figs. 1 and 2 provides a communication system for railway yards that is based on the closed circuit principle and is simple and reliable.

Although I have herein shown and described only one form of apparatus embodying my invention, it is understood that various changes and 60 modifications may be made therein within the scope of the appended claims without departing from the spirit and scope of my invention.

Having thus described my invention, what I 65 claim is:

1. A communication system for a railway yard, comprising a transmitting circuit which includes a track rail of each track of the yard for electrically transferring energy to a vehicle on any one of the tracks, transmitting apparatus coupled 70

- with said circuit and including a modulator-oscillator, circuit means connected with said transmitting apparatus and normally active to cause said modulator-oscillator to generate a predetermined signaling current for normally supplying the transmitting circuit with such signaling current, a control station including a microphone and a manually operable circuit controller, and other circuit means governed by said controller to render the first mentioned circuit means inactive and to connect said microphone with the transmitting apparatus for supplying a carrier telephone current to said transmitting circuit.
2. A communication system for a railway yard, comprising a transmitting circuit which includes a track rail of each track of the yard for electrically transferring energy to a vehicle on any one of the tracks, transmitting apparatus coupled with said circuit and including a modulator-oscillator, circuit means connected with said transmitting apparatus and normally active to cause said modulator-oscillator to generate a predetermined signaling current for normally supplying the transmitting circuit with such signaling current, a control station including a microphone and a manually operable circuit controller, other circuit means governed by said controller to render the first mentioned circuit means inactive and to connect said microphone with the transmitting apparatus for supplying a carrier telephone current to said transmitting circuit, and indication means including an indicator located at said control station and governed by said first mentioned circuit means to indicate that said first mentioned circuit means is active.
3. A communication system for a railway yard, comprising a transmitting circuit which includes a track rail of each track of the yard for electrically transferring energy to a vehicle on any one of the tracks, transmitting apparatus coupled with said circuit and including a modulator-oscillator, circuit means connected with said transmitting apparatus and normally active to cause said modulator-oscillator to generate a predetermined signaling current for normally supplying the transmitting circuit with such signaling current, a plurality of control stations located at selected points about the yard, said stations each including a microphone and a manually operable circuit controller, means governed by the circuit controller of each station to render said circuit means inactive and to connect the associated microphone with the transmitting apparatus to supply a carrier telephone current to the transmitting circuit, and other means governed by each circuit controller to render the remaining circuit controllers each ineffective to connect its associated microphone to the transmitting apparatus.
4. A communication system for a railway yard, comprising a transmitting circuit which includes a track rail of each track of the yard for electrically transferring energy to a vehicle on any one of the tracks, transmitting apparatus coupled with said circuit and including a modulator-oscillator, circuit means connected with said transmitting apparatus and normally active to cause said modulator-oscillator to generate a predetermined signaling current for normally supplying the transmitting circuit with such signaling current, a plurality of control stations located at selected points about the yard, said stations each including a microphone and a manually operable circuit controller, means governed by the circuit controller of each station to render the remaining circuit controllers each ineffective to connect its associated microphone to the transmitting apparatus to supply a carrier telephone current to the transmitting circuit, and other means governed by each circuit controller to render the remaining circuit controllers each ineffective to connect its associated microphone to the transmitting apparatus to supply a carrier telephone current to the transmitting circuit, and other means governed by each circuit controller to render the remaining circuit controllers each ineffective to connect its associated microphone to the transmitting apparatus, a first indication means governed by said circuit means and including an indicator at each control station to indicate at each station the active condition of said circuit means, and a second indication means governed by said controllers and including an indicator at each station to indicate when a microphone at one of the stations is made active.
5. A communication system for a railway yard, comprising a transmitting circuit which includes a track rail of each track of the yard for electrically transferring energy to a vehicle on any one of the tracks, transmitting apparatus coupled with said circuit and including a modulator-oscillator, circuit means connected with said transmitting apparatus and normally active to cause said modulator-oscillator to generate a predetermined signaling current for normally supplying the transmitting circuit with such signaling current, a plurality of control stations located at selected points about the yard, said stations each including a microphone and a manually operable circuit controller, means governed by the circuit controller of each station to render said circuit means inactive and to connect the associated microphone with the transmitting apparatus to supply a carrier telephone current to the transmitting circuit, other means governed by each circuit controller to render the remaining circuit controllers each ineffective to connect its associated microphone to the transmitting apparatus, a first indication means governed by said circuit means and including an indicator at each control station to indicate at each station the active condition of said circuit means, and another indicator at each control station and connected in parallel with the associated microphone to indicate when the microphone is effective and when communication is in progress at another control station.
6. A communication system for a railway yard comprising, a transmitting circuit including a rail of each track of the yard for the transfer of energy to a vehicle on any one of the tracks, transmitting apparatus coupled with said circuit and including a source of carrier current, a relay, circuit means including a contact of said relay and connected with said transmitting apparatus to supply the transmitting circuit with a signaling current which is equivalent to said carrier modulated by a predetermined frequency, a control station provided with a microphone and a circuit controller biased to a normal position, a first circuit including a normally closed contact of said controller and a winding of said relay to energize the relay for normally supplying the transmitting circuit with said signaling current to check that the transmitting circuit is in working order, and a second circuit including a normally open contact of said controller and said microphone and connected with the transmitting apparatus to modulate said carrier with voice frequencies for supplying the transmitting circuit with a carrier telephone current.
7. A communication system for a railway yard comprising, a transmitting circuit including a rail of each track of the yard for the transfer of energy to a vehicle on any one of the tracks,

- transmitting apparatus coupled with said circuit and including a source of carrier current, a relay, circuit means including a contact of said relay and connected with said transmitting apparatus 5 to supply the transmitting circuit with a signaling current which is equivalent to said carrier modulated by a predetermined frequency, two control stations each provided with a microphone and a circuit controller biased to a normal position, a first circuit including a normally closed contact of each of said controllers and a winding of said relay to energize the relay and condition the transmitting apparatus for normally supplying the transmitting circuit with 10 said signaling current to check that the transmitting circuit is in working order, and a second circuit means including a normally closed contact of each controller and a normally open contact of each controller as well as the microphones for connecting the microphone at the station at which the controller is operated with the transmitting apparatus to modulate the carrier with voice frequencies for supplying the transmitting circuit with a carrier telephone current and to render the remaining microphone 15 ineffective.
8. A communication system for a railway yard comprising, a transmitting circuit including a rail of each track of the yard for the transfer of energy to a vehicle on any one of the tracks, transmitting apparatus coupled with said circuit and including a source of carrier current, a relay, circuit means including a contact of said relay and connected with said transmitting apparatus to supply the transmitting circuit with a signaling current which is equivalent to said carrier modulated by a predetermined frequency, two control stations each provided with a microphone and a circuit controller biased to a normal position, a first circuit including a normally closed contact of each of said controllers and a winding of said relay to energize the relay and condition the transmitting apparatus for normally supplying the transmitting circuit with 20 said signaling current to check that the transmitting circuit is in working order, a second circuit including a normally closed contact of the controller at one station and a normally open contact of the controller at the other station as well as the microphone at said other station to connect the microphone with the transmitting apparatus, and a third circuit including a normally closed contact of the controller at said other station and a normally open contact of the controller at said one station as well as the microphone at said one station to connect that microphone with the transmitting circuit, whereby the signaling current is discontinued by the operation of either controller and telephone communication is effected from the station at which the controller is operated.
9. In combination with transmitting apparatus capable of modulating a carrier current with voice frequencies and of producing a signaling current equivalent to said carrier modulated at a predetermined frequency, a relay, circuit means including a contact of the relay to condition said transmitting apparatus to produce said signaling current, a first and a second control station spaced apart and each provided with a microphone and a manually operable circuit controller biased to a normal position, a first circuit including a normally closed contact of each of said controllers and a winding of the relay to energize said relay for normally conditioning the transmitting apparatus to produce said signaling current, a second circuit to connect the microphone of the first station to the transmitting apparatus and including a normally closed contact of the controller at said second station and a normally open contact of the controller at said first station, and a third circuit to connect the microphone of the second station to the transmitting apparatus and including a normally closed contact of the controller at said first station and a normally open contact of the controller at said second station, and an indication circuit including an indicator at each of said stations and a front contact of said relay.
10. In combination with transmitting apparatus capable of modulating a carrier current with voice frequencies and of producing a signaling current equivalent to said carrier modulated at a predetermined frequency, a relay, circuit means including a contact of the relay to condition said transmitting apparatus to produce said signaling current, a first and a second control station spaced apart and each provided with a microphone and a manually operable circuit controller biased to a normal position, a first circuit including a normally closed contact of each of said controllers and a winding of the relay to energize said relay for normally conditioning the transmitting apparatus to produce said signaling current, a second circuit to connect the microphone of the first station to the transmitting apparatus and including a normally closed contact of the controller at said second station and a normally open contact of the controller at said first station, a third circuit to connect the microphone of the second station to the transmitting apparatus and including a normally closed contact of the controller at said first station and a normally open contact of the controller at said second station, and an indication circuit including an indicator at each of said stations and a front contact of said relay.
11. In combination with transmitting apparatus capable of modulating a carrier current with voice frequencies and of producing a signaling current equivalent to said carrier modulated at a predetermined frequency, a relay, circuit means including a contact of the relay to condition said transmitting apparatus to produce said signaling current, a first and a second control station spaced apart and each provided with a microphone and a manually operable circuit controller biased to a normal position, a first circuit including a normally closed contact of each of said controllers and a winding of the relay to energize said relay for normally conditioning the transmitting apparatus to produce said signaling current, a second circuit to connect the microphone of the first station to the transmitting apparatus and including a normally closed contact of the controller at said second station and a normally open contact of the controller at said first station, a third circuit to connect the microphone of the second station to the transmitting apparatus and including a normally closed contact of the controller at said first station and a normally open contact of the controller at said second station, and an indication circuit including an indicator lamp at each station and a front contact of said relay, and another indicator lamp at each station connected in multiple with the associated microphone.
12. In combination with transmitting apparatus capable of modulating a carrier current with voice frequencies to produce a carrier telephone current, a first and a second control station spaced apart and each including a microphone

- and a manually operable circuit controller biased to a normal position, a first circuit to connect the microphone at the first station with the transmitting apparatus and including a normally closed contact of the controller at said second station and a normally open contact of the controller at said first station, a second circuit to connect the microphone at the second station with the transmitting apparatus and including a normally closed contact of the controller at said first station and a normally open contact of the controller at said second station, an indicator at the first station governed by said first circuit, and an indicator at said second station governed by said second circuit.
13. A communication system for a railway yard, comprising a normally closed transmitting

5 circuit which includes in multiple a track rail of each track of the yard for transfer of energy to a vehicle on any one of the tracks, a winding interposed in said circuit, a source of signaling current of a predetermined frequency, a control station including a microphone and a circuit controller, means including a normally closed contact of said controller to couple said source with said winding for normally supplying the transmitting circuit with such signaling current to 10 check that the transmitting circuit is in working order, and other means including a normally open contact of said controller to at times couple the microphone with said winding for supplying a telephone current to said transmitting circuit. 15

RALPH R. KEMMERER.
